SALAD SERVER

Gunnar Cyren, Gavle, Sweden, assignor to Dansk
Designs Ltd., Mount Kisco, N.Y.

Filed Nov. 1, 1972, Ser. No. 302,969

Term of patent 14 years

Int. Cl. D7—03

U.S. Cl. D7—104

FIG. 1 is a top plan view of a salad server embodying my novel design;
FIG. 2 is a side elevational view thereof;
FIG. 3 is a right end elevational view thereof;
FIG. 4 is a left end elevational view thereof;
FIG. 5 is a bottom plan view thereof; and
FIG. 6 is a sectional view thereof, taken along line 6—6 of FIG. 1.

I claim:

The ornamental design for a salad server, as shown.
